UNITED STATES PATENT OFFICE.

FRANK G. CALDWELL, OF WHEELING, WEST VIRGINIA.

CRATE FOR SHEET METAL.

SPECIFICATION forming part of Letters Patent No. 440,009, dated November 4, 1890.

Application filed July 29, 1890. Serial No. 360,324. (No model.)

To all whom it may concern:

Be it known that I, FRANK G. CALDWELL, a citizen of the United States, residing at Wheeling, in the county of Ohio and State of West Virginia, have invented new and useful Improvements in Means for Crating Sheet-Iron Panels or Plates, of which the following is a specification.

This invention has for its object to provide novel, simple, efficient, and economical apparatus or means for crating corrugated or crimped sheet-iron panels or plates for transportation, whereby a package containing a definite number of superimposed panels or plates can be shipped with safety in a flat, compact, and stable form in such manner as to be readily and conveniently handled without liability of the parts separating by breakage of the package.

To accomplish this object my invention involves the features of construction, the combination or arrangement of devices, and the principles of operation, hereinafter described and claimed, reference being made to the accompanying drawings, in which—

Figure 1 is a perspective view of a package of corrugated or crimped sheet-iron panels or plates secured together for shipment in accordance with my invention. Fig. 2 is a longitudinal sectional view taken through one of the ribbons or strips, and Fig. 3 is a detail perspective view showing the parts separated and as they appear before being applied to the sheet-iron panels or plates.

In order to enable those skilled in the art to make and use my invention, I will now describe the same in detail, referring to the drawings, wherein—

The numerals 1 and 2 indicate a pair of transverse clamping rods or bars having undulated or zigzagged inner surfaces conforming exactly or approximately to the corrugated or crimped form of the sheet-metal panels or plates, and preferably provided with rectilinear outer surfaces 3, all in such manner that two of these rods or bars can be applied to the end portion of a series of corrugated or crimped sheet-iron panels or plates 4, as indicated in Fig. 1. The extremities of each pair of rods or bars are securely connected together by sheet-metal or other me-

tallic clips 5, the ends of which are bent around the extremities of the rods or bars and attached by nails 6 or otherwise. The two pairs of rods or bars are connected by longitudinal strips or ribbons 7, one or more, which have their extremities turned at right angles to their body portions and nailed or otherwise attached, as at 8, to the rods or bars.

In practice several of the corrugated or crimped sheet-iron panels or plates are placed one upon the other and the longitudinal strips or ribbons are then laid thereupon, so that their end portions project beyond the edges of the panels or plates, and then another series of the corrugated panels or plates is laid upon the ribbons or strips, after which a pair of the rods or bars is applied to each end of the package in such manner as to clamp the superimposed panels or plates between them. The extremities of each pair of rods or bars are then connected together by the clips, which are nailed or otherwise securely fastened in place, and finally the end portions of the strips or ribbons are bent and nailed or otherwise suitably attached to the rods or bars at each end of the package. By this construction a series of superimposed corrugated panels or plates are clamped at the end portions by the pairs of rods or bars, and the two sections or parts comprising each pair of rods or bars are firmly clamped upon the sheet-iron panels or plates by the end clips, while the longitudinal strips or ribbons retain the rods or bars from longitudinal movement or displacement, whereby the entire package of panels or plates is secured in a compact form suitable for safe shipment and without liability of the parts becoming separated by breakage of the package.

The construction of the transverse rods or bars with undulated or zigzagged inner surfaces permit such bars to be rigidly clamped down upon the panels or plates, and inasmuch as the adjoining surfaces of the rods or bars and the panels or plates conform exactly or approximately to each other the corrugations or crimps of the sheet-iron panels or plates are not liable to be pressed out of correct shape by the clamping action of the rods or bars.

The crating of the sheet-iron panels or

plates by means of the transverse rods or bars, the end clips, and the longitudinal strips or ribbons, provides a package which is practically rigid and one structure, and being in 5 a flattened, compact, and stable form, it is readily and conveniently handled during transportation without danger of the panels or plates becoming separated.

Having thus described my invention, what 10 I claim is—

1. A crating apparatus for corrugated or crimped sheet-iron panels or plates, consisting of two pairs of rods or bars having undulated or zigzagged inner surfaces conforming 15 approximately to the crimped form of the panels or plates, the end clips for connecting the ends of the rods or bars and clamping the latter upon the package of panels or plates, and the longitudinal metallic ribbons or strips

connected at their ends with the pairs of rods 20 or bars, substantially as described.

2. A package of corrugated or crimped superimposed sheet-iron panels or plates rigidly clamped together at their ends by pairs of clamping rods or bars having undulated 25 or zigzagged inner surfaces and united at their ends by clips, combined with longitudinal ribbons or strips laid between the plates and connected at their ends with the pairs of clamping rods or bars, substantially as de- 30 scribed.

In testimony whereof I have affixed my signature in presence of two witnesses.

FRANK G. CALDWELL.
